(57) CLAIM

The ornamental design for a brush handle, as shown and described.

DESCRIPTION

FIG. 1 is a perspective view of a brush handle showing my new design with broken lines showing a brush head being for illustrative purposes only and forming no part of the claimed design;

FIG. 2 is a side elevational view thereof, the opposite side with the exception of inward curvature seen in FIG. 3, being a mirror image;

FIG. 3 is a bottom plan view thereof;

FIG. 4 is a front elevational view thereof;

FIG. 5 is a rear elevational view thereof; and,

FIG. 6 is a top plan view thereof.
